[57] CLAIM

We claim the ornamental design for a ski damper, as shown and described.

DESCRIPTION

FIG. 1 is a top plan view of a first embodiment of applicants' ski damper design, showing the damper mounted in a ski with a visible damper light;

FIG. 2 is a side view of the embodiment of FIG. 1; and, FIG. 3 is an end view of the embodiment of FIG. 1 from the trailing end of the ski, the opposite-end view not being visible in use owing to obstruction by the curved tip of the ski;

FIG. 4 is a top plan view of a second embodiment of applicants' ski damper design, showing the damper mounted in a ski with a visible damper light;

FIG. 5 is a side view of the embodiment of FIG. 4; and, FIG. 6 is an end view of the embodiment of FIG. 4 from the trailing end of the ski, the opposite-end view not being visible in use owing to obstruction by the curved tip of the ski;

FIG. 7 shows a top plan view of a third embodiment of applicants' ski damper design, showing the ski partially in phantom, the side and end views of this embodiment being substantially the same as FIGS. 5 and 6; and,

FIG. 8 shows a top plan view of a fourth embodiment of applicants' ski damper design, showing the ski partially in phantom, the side and end views of this embodiment being substantially the same as FIGS. 5 and 6.
